UNITED STATES PATENT OFFICE

JOB HUTCHINSON, OF SAUGERTIES, NEW YORK

VACUUM CLEANER

Application filed June 3, 1924. Serial No. 717,494.

This invention relates to a portable machine for cleaning carpets, rugs and the like, by means of air currents, and more particularly to a machine in which air jets and suction are combined in a circulation system.

It has heretofore been proposed to create at the nozzle of a vacuum cleaner a sufficient suction to lift the carpet from the floor and draw air through it. It has been found, however, that when suction strong enough to flex the carpet and produce the desired cleaning effect is employed, the carpet is drawn so tightly against the nozzle that it tends to cling, and thus prevent the free movement of the device over the floor.

It has also been proposed to employ a revolving brush in connection with such a suction nozzle, so that the brush beats against the raised or flexed portion of the carpet within the nozzle. The presence of the brush, however, necessitates the use of a very wide open nozzle, and the area is so great that the vacuum must be kept inadequately low to prevent undue clinging of the carpet, as otherwise too much effort would be required to propel the nozzle over the floor.

A vacuum of three or four inches of mercury will clean the average carpet thoroughly, by raising the same from the floor under the nozzle, as described above, thus causing the slight bend to break up the layer of dirt and grit embedded at the bottom of the nap, provided a means can be found to prevent objectionable clinging of the carpet to the nozzle when such a degree of vacuum is used.

One of the objects of the present invention is, therefore, to provide means for preventing an effectively high vacuum from causing excessive clinging or sticking of the carpet to the nozzle.

A further object is to accomplish this by means of air jets, which shall, at the same time, enter or blow into the carpet at the bend and assist in loosening up and dislodging the dirt. A subsidiary object is to make possible, by the above means, the use of a revolving brush in the nozzle, if desired, to still further aid in removing the dirt from the carpet.

50. Another object of the invention is to pro-

vide an improved motor driven pump having means by which its stroke may be varied at will to regulate the vacuum, without waste of energy.

Another object is to provide an improved dust collector or filter screen, and means for effectively cleaning the same automatically while in use.

A further object is to devise improved means for storing and carrying suction hose on the portable cleaning machine.

A still further object of the invention is to provide improved means for supporting and propelling the machine over the floor, and for adjusting the height of that part thereof to which the nozzle is attached.

The general object is to provide a complete portable machine or unit especially designed to meet the needs of hotels, office buildings, theaters, and other public institutions, and other specific objects and advantages will further appear from the following description.

In order that the invention may be readily understood, reference is had to the accompanying drawings, forming part of this specification, and in which:—

Fig. 1 is a side elevation of the complete machine;

Fig. 2 is a plan view thereof;

Fig. 3 is a rear elevation thereof on an enlarged scale;

Fig. 4 is a front elevation thereof on a similar scale;

Fig. 5 is an inverted plan view of the cleaning nozzle, which is attached to the front of the machine;

Fig. 6 is a central, longitudinal, vertical section through the complete machine, substantially on the line 6—6 of Fig. 2;

Fig. 7 is a transverse section substantially on the line 7—7 of Fig. 6;

Fig. 8 is a similar transverse section substantially on the line 8—8 of Fig. 6;

Fig. 9 is an elevation of the end of one of the castings forming part of the body or casing of the machine, parts being broken away and parts being shown in section;

Fig. 10 is an elevation of another one of the

castings going to make up the body of the machine;

Fig. 11 is a fragmentary, sectional elevation substantially on the line 11—11 of Fig. 9;

Fig. 12 is a vertical transverse section on the line 12—12 of Fig. 10;

Fig. 13 is a sectional elevation substantially on the line 13—13 of Fig. 9, showing some of the details of the control mechanism;

Fig. 14 is a transverse section through the complete machine, substantially on the line 14—14 of Fig. 6;

Fig. 15 is an enlarged view, partly in section and partly in elevation, of one of the differential mechanisms;

Fig. 16 is a transverse section on the line 16—16 of Fig. 15;

Fig. 17 is a horizontal section on the line 17—17 of Fig. 18, showing one of the contact sleeves and brushes associated with the electrical conductor reel;

Fig. 18 is a vertical section on an enlarged scale through the central part of such reel, showing the contact sleeves and brushes complete; and

Fig. 19 is a vertical sectional view similar to Fig. 6, but showing a modified construction of cleaning nozzle at the front end of the machine.

General organization

My improved portable cleaning unit comprises a substantially rectangular, elongated casing or body, which is made up of three castings bolted together. These castings comprise a chamber or compartment 1, shown at the left in Fig. 6, a central plate or partition 2, shown in detail in Figs. 10 and 12, and a casting or compartment 3, shown at the right in Fig. 6. The left hand end of the compartment 1 is closed by means of a head or plate 1^a, secured by suitable bolts and the right hand end of the casting or compartment 3 is closed by means of a head or end plate 4. An auxiliary hood or cover 5 is mounted at the center of the plate 4, to enclose certain working parts hereinafter referred to.

The machine, as a whole, is mounted on a pair of relatively large main wheels 6, which are preferably formed of pressed sheet metal, and provided with solid rubber tires. As shown in Fig. 7, these wheels are journaled by means of ball bearings 7, on studs or stub axles 8, set into the side wall of the casting 1.

Secured to the rear end plate 1^a of the machine is a powerful electric motor 9, having a drum-shaped or cylindrical frame, one end of which is secured to the machine by bolts 9^a, with the axis or shaft of the motor in a horizontal position and with the motor itself projecting rearwardly from the body of the machine. The motor shaft 10 is connected

by means of a coupling 11, with another shaft 12, connected in turn at its end by a coupling 14, with a third shaft 13, the three shaft sections 10, 12 and 13 constituting a continuous line of shafting which extends centrally and longitudinally through the body of the machine from one end to the other. The shaft 12 is supported at one end in ball bearings 15, carried by a dish-shaped portion 1^b of the end wall 1^a, and at the other end by ball bearings 16, supported in the central plate or casting 2. The shaft section 13 is journaled at its outer end in ball bearings 17, supported by the end plate 4. The shaft 13 extends centrally through a dust collecting drum or air filter, hereinafter described, and a cleaning nozzle is attached to the front end of the machine adjacent the dust collector.

It will be particularly noted at this point, that the axis of the main supporting wheels 6 is located near the center of gravity of the machine as a whole. Although this axis is considerably to the left of the geometrical center of the machine, as viewed in Fig. 6, it will be noted that the motor 9 is relatively heavy, while the dust collector is relatively light, and thus the total weight of the unit is almost balanced about the axis of the main wheels 6. This makes it very easy to tilt the machine about such axis as is necessary in steering.

Within the compartment or casting 1 is mounted a pump mechanism, now to be described, and it may be pointed out that packing washers of felt or the like, as indicated at 18 in Fig. 6, are provided to prevent leakage of air around the shaft sections 12 and 13.

The pumping mechanism

As stated in the preamble, I contemplate producing a complete circulation of air through the machine, and to this end, I have devised an improved nozzle and efficient pumping mechanism so designed as to draw air in at one side, to create a partial vacuum, and to deliver the same air under pressure, at the other side. This improved pump operates entirely without valves of any kind, and is therefore exceptionally free from trouble.

Referring to Fig. 6, the pump comprises a drum or cylinder 19, having a circular series of parallel open ended cylinders 20, eight of such cylinders being shown (see Fig. 7). The drum 19 is rigidly keyed to and rotates with the shaft 12, and is mounted on said shaft in such a position that its right hand end, as viewed in Fig. 6, works very close to the face of the plate or casting 2. Both of these parts are carefully machined so that the necessary clearance between them is reduced to a minimum. Furthermore, the face of the plate 2 is provided with an upstanding flange or rim 44, which closely surrounds the

drum 19. In each cylinder 20 reciprocates a piston 21, these pistons being of special construction. As shown in Figure 6, each piston is substantially spherical in form, being formed of two sections held together by the threaded end of the piston rod 23, and each piston is provided with a packing ring 22, at its point of contact with the cylinder, such packing ring preferably being cylindrical in cross section, as shown. By virtue of the special shape of the pistons and packing rings, such pistons are capable of slight rocking or angular movement, relative to the axes of the cylinders, without causing binding or cramping.

The rear or outer ends of the piston rods 23 are provided with balls 24 which are received in spherical sockets formed in a disc constructed of a pair of pressed sheet metal members 25, the sockets being formed partly in each member, and the members being fitted together as shown in Figs. 6 and 14. This disc is also driven by the shaft 12, but is capable of angular movement relative thereto. To this end, the disc is secured to the shaft by means of a universal joint comprising a pair of pivots 26, one end of which is secured to the disc and the other end of which is mounted in a ring or frame 27. A second pair of pivots 28, at right angles to the first, engages the ring 27 and projects rigidly from diametrically opposite sides of a hub 29, attached to the shaft 12. Thus, the disc is driven through the pivot pins 26 and 28, but by virtue of the angular relation of these pins, it is permitted to "wobble" freely, relative to the shaft.

The outer edges of the members 25, forming the above described disc, are spread apart, as indicated at 30, to receive between them the central flange or member 31, of a ring 32, T-shaped in cross section, as clearly shown in Fig. 6, suitable ball bearings 33 being interposed between each side of the flange 31 and the respective disc portion 30.

The ring 32 is pivotally mounted by means of pins 35 (see Fig. 14) to swing about a horizontal axis and projecting from the lower side thereof is an arm or lever 34 terminating in a bifurcated portion provided with alined slots 36, which slots loosely engage a pair of pins 37, projecting from the opposite sides of a nut 38, working on a horizontal screw 39. This screw passes through a suitable journal 41, carried by the rear end wall of the casting 1, and is provided at its outer end with a hand wheel 40. The inner end of the screw is journaled at 42 in a suitable boss and a stop sleeve 43 surrounds the screw 39, and is interposed between such boss and the nut 38, in order to limit the inward movement of such nut. The nut is shown in its extreme position in Fig. 6, and when in this position, it will be noted that the stroke of the pump pistons is a maximum.

It will be observed that as the drum 19 and disc 25 revolve together with the shaft 12, each piston is caused to execute a complete reciprocation once in every revolution. By turning the hand wheel 40, the nut 38 may be moved toward the left, as viewed in Fig. 6, bringing the disc 25 more and more nearly into a position at right angles to the shaft 12, and thus gradually decreasing the stroke of the pistons. When the disc 25 occupies a position exactly at right angles to the shaft 12, it is obvious that the pistons will not reciprocate at all, and that the only load on the motor will be that due to friction. If the movement of the nut 38 is continued from this point, still further to the left, the disc will be inclined in the opposite direction and the action of the pistons will be reversed. That is to say, that portion of the revolution of the pump drum which formerly caused a suction stroke of the pistons, will now cause a compression stroke. Thus, by manipulating the wheel 40, the action of the pump may be varied continuously from a maximum in one direction, through zero, to a maximum in the other direction, and this without loss of efficiency.

Referring now to Figs. 9 and 10, it will be seen that the plate or casting 2, within the area which is transversed by the adjacent ends of the cylinders 20, is provided with a pair of arc-shaped slots or ports 45, 46, and that a similar pair of ports 47 and 48, registering therewith, is provided in the adjacent face of the casting 3. Disregarding, for a moment, the question of what these slots or ports communicate with, it will be observed that, with the normal setting of the disc 25, as the cylinders revolve in a clockwise direction, as viewed in Figs. 7, 9 and 10, the pistons will operate to successively suck air into each cylinder during the time that it is traveling over the ports 45 and 47, and will operate to successively force air out of each cylinder during the time it is traveling over the ports 46 and 48. Thus, the ports 45 and 47 are the intake or suction ports, while the ports 46 and 48 are the discharge or compression ports.

The face of the casting 3, adjacent the casting 2, is provided with an annular shoulder 49, (see Fig. 9) within which a corresponding boss 49^a (see Fig. 12) on the casting 2 fits. That portion of the casting 3, adjacent the ports 47 and 48, is provided with suitable walls and partitions for the purpose of forming conduits establishing communication between the respective ports and the dust collector and cleaning nozzle, as will be herein-after more fully explained. The casting contains vertical alined partitions 50 and 51 (see Fig. 9) for separating the suction and compression sides of the mechanism. Between these two partitions is disposed a gear box having a horizontal upper wall 52, a

horizontal bottom wall 53, and side walls 54. Below the partition 51 is a horizontal partition 55, and spaced from this a suitable distance is a second horizontal partition 56. A 5 vertical partition 57, at right angles to 50 and 51, and spaced back from the face of the casting 3, is provided as shown in Fig. 6, and a similar wall 58 in the same plane therewith, extends across the upper part of the 10 said gear box. The partitions 50 and 51 terminate in a transverse wall 59, which extends across the casting parallel with the face in which the slots 47 and 48 are formed.

These various walls and partitions give 15 rise to the formation of a conduit 60, which opens out through the wall 59 at one end and which communicates at its other end with the port 47, and a conduit 61, lying between the walls 55 and 56, which communicates with 20 the port 48. A pair of pipes 62, arranged one at each side of the machine, extend from the conduit 61 forwardly to the front end plate 4, of the machine (see Figs. 6 and 8).

The dust collector or air filter

25 Mounted in the compartment 3 between the wall 59 and end wall 4, is my improved dust collector or separator. This, in general, is drum-shaped and is concentric with the shaft 13. It comprises a central sleeve 63, journaled on the shaft 13, and on this sleeve 63 are fitted a series of discs 64, held in spaced parallel relation by means of spacing sleeves or collars 67. The outer peripheries of the 30 disc 64 are preferably provided with enlarged rounded rims 65, and the central portion of the discs is cut away to form supporting spiders 66, as clearly shown in Fig. 8, thus leaving a free air passage through the center of the structure.

40 Alternating with the discs 64, is a series of rings 68, which may be wires or cords, and a suitable filter cloth 70 is stretched over the rims 65 and thence under the rings 68, back 45 and forth, in and out, throughout the length of the drum. Preferably a tubular fabric, capable of fitting over the discs 64 is employed, such fabric being then drawn in between the discs by means of the rings 68. 50 The extreme ends of the fabric or cloth are secured to channel-shaped end rings, 69 preferably formed of sheet metal.

55 The above construction gives rise to a filter having porous walls of very large area, the cloth extending in substantially radial planes from the rings 68 to the rims 65 of the discs 64. While these surfaces are substantially plain radial surfaces, they are in fact, very obtuse cones. In any event, however, they 60 are straight line surfaces of single curvature.

In operation, dust laden air is drawn through the screen or filter from the outside toward the inside thereof, so that dust tends to accumulate on the above described surfaces. In order to effectively and continu-

ously remove this dust I provide a series of stationary brushes 71, formed on transversely extending rods 72, see Fig. 8, supported in frames 73. As will be seen from Fig. 6, I mount one of these brushes in each channel-shaped space between adjacent radial walls of the filter, at a point below the shaft 13, and preferably make each brush of somewhat tapering form, as shown in Fig. 8, so as to fit the slightly tapering channel in which it is mounted and effectively engage both adjacent screen surfaces throughout substantially their whole radius.

70 Means are provided for rotating the filter while the brushes remain stationary, and therefore, as the filter cloth is moved past the brushes, the accumulated dust is scraped off and falls into a dust pan 86, located below the filter.

75 Means for rotating the filter comprise a gear wheel 74 secured to the channel ring 69, at the rear or inner end of the drum, and having a central opening 75, which registers with the open end of conduit 60, extending to the suction port 47 of the pumping mechanism. A felt ring 76 is interposed between the face of the wheel 74 and the plate 59 of the casting 3, in order to prevent leakage of air.

80 Referring to Fig. 11, it will be seen that this gear wheel 74 meshes with a small pinion 77, carried by a stub shaft 78, journaled in the plate 59, and carrying at its outer end a beveled pinion 79, to which rotation is imparted by means hereinafter described.

The cleaning nozzle

85 To the front end of the body of the machine is attached a cleaning nozzle of improved construction, the shape of which is best shown in Figs. 4, 5 and 6. This nozzle is designated in its entirety by the reference numeral 80, and comprises a vacuum compartment 81, having its lower end open to form a suction mouth, which is relatively long and narrow, 90 as shown in Fig. 5, and extends substantially across the width of the machine. The vacuum or suction compartment 81 is provided with a nipple or connection 82, controlled by a rotary plug valve 83, and adapted to be attached by means of lugs and nuts 84, to the front wall 85 of the dirt pan 86, already referred to. This pan rests upon the bottom or floor of the casting 3, and underlies the entire dust collector or filter. Thus, when the pumping device is running, a partial vacuum is produced at the ports 45 and 47, which causes air to flow in through the suction mouth, and compartment 81, through the valve 83, into the space below the dust 100 collector or filter, and thence through the filter and into conduit 60.

105 In practice, the pump is preferably so designed as to produce a vacuum equal to three or four inches of mercury and such a vacuum 110

as this produces a very efficient cleaning action. It is particularly effective in cleaning carpets and the like, and even with a suction mouth as narrow as that illustrated, it is sufficient to lift the carpet from the floor, as indicated at α in Fig. 6, and thus produce a bend or flexure in the carpet which tends to break up and loosen any dirt which may be embedded in the lower part of the nap. It is found, however, that with such a strong suction as this, the carpet tends to cling so tightly to the nozzle around the suction mouth as to seriously interfere with free movement of the machine over the floor. One of the most important features of the present invention resides in the means which I have devised for overcoming this difficulty and for preventing objectionable clinging of the carpet. This, I accomplish, in the following manner.

In each side of the central or suction compartment 81 of the nozzle, I provide a pressure compartment 94. These pressure compartments are connected by means of a pair of upstanding pipes 88, see Fig. 4, and nipples 89, with the ends of the pipes 62 extending forwardly from the pressure conduit 61, connected with the delivery side of the pump. Mounted at the top of each pipe 88 is a safety or relief valve 90, held to its seat by a spring 91, the tension of which may be adjusted by a nut 92, the housing surrounding each valve being provided with openings 93, to permit the escape of air. By adjusting the nuts 92, the valves 90 may be set to blow off at any desired pressure, and in this way, the maximum pressure developed may be regulated as desired.

The lower walls of the pressure compartments 94 of the nozzle are provided adjacent the suction mouth, with a series of jet orifices 95, (see Figs. 5 and 6), these orifices being so positioned as to direct jets of compressed air downwardly and inwardly toward each other and across the suction mouth. The effect of these jets is to practically eliminate the friction between the carpet and the edges of the suction mouth, and thus substantially prevent clinging of the carpet. At the same time, these jets impinge upon and enter the carpet at this point of flexure, thus materially assisting in dislodging any embedded dirt or grit. The dirt loosened or dislodged by these jets is immediately sucked up into the suction mouth and through the compartment 81 and valve 88, into the dirt pan 86, while the finer particles lodge against the dust collector or filter, and are eventually removed by the brushes 71.

By virtue of the above combination of suction and pressure jets, I am enabled to employ a relatively high vacuum necessary for efficient cleaning, and at the same time, prevent objectionable clinging of the carpet. Moreover, the jets materially aid in removing foreign matter from the carpet nap.

While, in most cases, it is believed that the

form of nozzle shown in Figs. 4, 5 and 6 will efficiently and satisfactorily clean any ordinary carpet, it may, in some cases, be desirable to employ a brush in connection with the pneumatic means. This is shown in Fig. 19, 70 in which a somewhat different form of nozzle 80' is illustrated. This nozzle, however, is provided with a suction compartment 81' and with a pair of pressure compartments 94', and also with the jet orifices 95, as above described. The suction mouth is, however, made much wider and in such mouth is mounted a rotary brush 163, geared by means of a belt 164, to a pulley 165, carried at the extreme end of the shaft 13. Instead of the housing 80, shown in the other figures, the front wall of the nozzle itself is extended upwardly, so as to enclose the belt and pulley, as shown at 162.

With the arrangement shown in Fig. 19, 85 the mechanical effect of the rotary brush, beating against the carpet at the point of flexure, is added to that of the suction and air jets, and even though the carpet is lifted from the floor, and the mouth of the nozzle is relatively wide, the air jets will prevent excessive sticking or clinging of the carpet to the nozzle.

The suction hose

While the above described cleaning nozzle, either with or without the brush, is designed for cleaning extended areas such as large halls or corridors, the machine is also equipped with convenient means for cleaning smaller areas or compartments, such as bed rooms, and the like, as well as for cleaning the dust from furniture, draperies, and the like. To this end, I provide one or more suction pipes 96, located in the lower part of the compartment or casting 1, and with their inner ends extending through registering openings 98 and 99, formed in the castings 2 and 3, respectively (see Figs. 9 and 10). These pipes communicate with a passageway 97, which opens into the dust collector chamber. Therefore, when the pump is running, a partial vacuum is produced through the dust collector or air filter in the pipe or pipes 96.

To the outer or rear end of one of these pipes 96 is attached a hose connection or coupling 100, (see Fig. 3) to which is secured a suitable length of suction hose 101, the other end of which, when not in use, is conveniently attached to a coupling 102, at the other side of the machine. It will be observed that this hose 101, when not in use, is conveniently stored by being wound around the drum-shaped motor frame 9. This is a feature of considerable practical importance, since in a portable unit in the kind under discussion, the question of storing and carrying suction hose is quite a problem.

In order to carry an additional length of hose, I provide a guiding handle for steering 130

the machine, of trough shape in cross section, so as to receive a piece of hose. This guiding handle is illustrated at 103, and as shown in Fig. 3, is substantially U-shape, with its ends rigidly anchored to the end plate 1 of the machine, as shown at 104. By reference to Figs. 1, 2 and 4, it will be seen that this handle 103 is also U-shaped or trough shaped in cross section, and affords a channel in which a piece of hose 108 may lie, the hose being held in position by means of a clip or the like 103^a. Extending forwardly from the ends 104 of the handle 103, are a pair of storage compartments or chambers, cylindrical in cross section, and comprising aligned openings 105, 106 and 107, formed in the castings 1, 2 and 3, respectively. In other words, the arrangement is such that the end portions of the hose 108, supported by the handle 103, may extend into and be housed within these aligned openings or chambers, so that quite a length of hose may be thus stored. In practice, and when required, the hose 108 may be removed and connected to the free end of the hose 101, the latter being of course uncoiled from the motor, and these two pieces, when coupled, providing hose of sufficient length for practically any ordinary purposes. Suitable nozzles or vacuum tools for attachment to the end of the hose may be supported in clips 109 (see Fig. 3) and the nozzles themselves may also be stored within a compartment 110, formed at one side of the lower part of the casting 1. At the opposite side of this casting may be formed a similar compartment or kit for containing ordinary tools or other supplies.

Supporting and propelling means

One of the important objects of the invention is to provide means whereby the machine may be propelled over the floor by the same motor which operates the pump, in order to lighten the work of the operator. To this end, I provide the shaft 113, at a point within the gear box 52—54, with a worm 112, and arranged to mesh with this worm is a worm wheel 113, secured to a short shaft 114. This is journaled in suitable bearings 115, one on each side of the worm wheel 113, (see Fig. 9). Each end of the shaft 114 projects into the housing of a differential mechanism 116. Each of these housings is formed of two halves or sections held together by screws 116^a (see Fig. 15) and to the end of the shaft 114 is secured a beveled gear 117. A similar beveled gear 118 is also mounted within the housing 116, and rigid with each gear 118, is a shaft 121, extending out through the side walls of the casting 3. Planet gears 119 mesh with the two gears 117 and 118 and are carried on stub shafts 120, journaled in the housing 116.

Secured to one of the shafts 121 is a beveled pinion 122, which meshes with the bevel

gears 79, which rotates the dust collector or filter, as above described.

With the parts so far described, it is obvious that as the worm wheel 113 is driven, the two differential housings 116 will idly rotate and no power will be transmitted to the shafts 121. Means for locking the housings against rotation are, however, provided. This comprises a sleeve 123, journaled on one of the shafts 121, and secured at its inner end to an arm 124. This is attached by means of a pin and slot connection to the free end of an arm or lever 125, secured to a rock shaft 126, journaled in the side walls 54 of the gear box, and carrying a pair of short arms 127, spaced apart a distance corresponding with that between the two differential housings 116. Pivotedly connected with each arm 127 is a sliding bolt 128, the lower end of which is adapted to engage in notches 129, formed on the periphery of the differential housings.

Secured to the outer end of the sleeve 123 is a lever arm 130, connected by a link 131, to the lower end of a control lever 132, pivotally mounted at the rear end of the machine within easy reach of the operator. It is therefore obvious that by manipulating the lever 132, the differential housings 116 may be locked against rotation when desired, and that when so locked, power will be transmitted from the worm wheel 113 to the shafts 121. In other words, the mechanism just described serves the double function of a clutch and differential.

Secured to the outer ends of each shaft 121 is a pinion 133, which meshes with a large gear 134, journaled on the hub 6^a of the wheel 6. The gear 134 is locked to the wheel 6 by means of set screws 135, carried by the wheel 6 and engaging lugs on the gear. These screws are, of course, in engagement with the lugs when the machine is being propelled by power, but they may be disengaged when it is desired to propel the machine by hand, as when transporting it from place to place. In this way, the operator is relieved from the frictional drag which would otherwise result from the engagement of the gearing.

To support the front end of the machine, I provide a pair of relatively small wheels 136, and in order to adjust the height of the cleaning nozzle 80 relative to the carpet, it is necessary that these wheels be made adjustable. I accomplish this by mounting the wheels 136 on cranks 137 (see Fig. 8) carried at the ends of a crank shaft 138, extending under the machine. To one end of this crank shaft is secured a worm wheel 139, which meshes with a worm 140 (see Fig. 4) carried at the lower end of a vertical shaft 141, journaled in brackets 142, and provided at its upper end with a hand wheel 143, by means of which it may be turned. Thrust collars 141^a are secured to the shaft 141 adjacent the bearings 142 to prevent endwise movement.

thereof, and when this shaft is turned, it will be obvious that the crank shaft 138 is correspondingly rocked in its bearings and that, owing to the cranks 137, the front end of the machine and the nozzle will be accordingly raised or lowered.

In order to supply current to the motor, and at the same time permit the machine to operate at any desired distance from an electric receptacle or socket without danger of the cord becoming damaged or tangled, I equip the machine with a reel for holding the conductor cord. The cord itself containing the usual two conductors is indicated at 144 and is provided at its end with the usual plug 145. The cord is preferably led through a guide 146, so as to insure its winding properly on the reel.

The reel itself preferably comprises a pair of spaced discs 147, having a central hub 147^a (see Fig. 18) into the interior of which, through an insulating bushing 147^b, the inner end of the conductor cord is led. The reel is provided with a central journal box or sleeve 149, which turns freely upon a spindle consisting of a bolt 148, set vertically into the top of the casting 3, so that the reel itself is horizontal.

The inner ends of the electrical conductors contained in the cord are soldered or otherwise secured to a pair of concentric conducting sleeves or rings 150 and 151, insulated from the journal box 149 and from each other by insulating bushings 152, the inner sleeve 150 preferably being longer than the outer one. These sleeves, of course, turn with the reel.

In order to establish electrical connection with the sleeves 150, 151, I provide a pair of brushes 154, 155, each in the nature of a split ring, adapted to embrace its respective sleeve, as shown in Fig. 17. These brushes or split rings are carried by shanks 156, supported by a block of insulation 157, mounted on a suitable bracket 159, and a cover or housing 158 of insulating material fits over and encloses all of the metallic current carrying parts above described, so as to avoid the possibility of shock or short circuit.

From the shanks 156 of the contact brushes extend suitable conductors, (not shown) through a switch 160, and through the usual rheostat or starting box 161 to the motor 9.

Operation

It will, of course, be understood that when suction hose attached to the pipe 96, is being employed, the valve 83 at the cleaning nozzle is closed, so as to create a partial vacuum in the dust collector chamber.

Furthermore, since the cleaning nozzle 80 is held in position by lugs or screws 84 and 87, (see Figs. 1 and 4), it can be readily detached and removed when not in use, the nipples 82 and 89 slipping readily out of their

respective pipe connections. When this cleaning nozzle is removed, a hose may be connected to the opening in the dirt pan in which the nipple 82 formerly fitted. Thus, I have provided means for connecting a hose to either the front or rear or both of the machines, as may be desired.

Although the brushes 71 will effectively prevent undue accumulation of dust upon the porous walls of the filter or dust collector, as the latter is rotated, it may be sometimes desirable to blow air back through the dust collector in a direction reverse to that of the normal flow. To accomplish this, it is only necessary to manipulate the hand wheel 40 so as to swing the disc 25 to the opposite side of the perpendicular from that shown in Fig. 6. When this is done, air is delivered from the cylinders 20, through the ports 45 and 47, and conduit 60, into the interior of the dust collector, thus blowing through the porous walls and serving to clean and dislodge the dust from the outer surface thereof.

It will be observed that the dust collector is rotated continuously so long as the machine is being propelled over the floor, and that by disconnecting the screws 135 from the gear wheels 134, the dust collector may be caused to rotate even when the machine is standing still.

What I claim is:—

1. A vacuum cleaner comprising an elongated body, a motor at one end of said body, a suction nozzle at the other end thereof, a dust collector adjacent said nozzle, a horizontal motor-driven shaft extending longitudinally of said body, pump mechanism located adjacent the motor and driven by said shaft, supporting wheels and gearing driven by said shaft for propelling the cleaner over the floor, said gearing being located between said dust collector and pumping mechanism.

2. In a vacuum cleaner, the combination with a casing having a closed chamber, a suction producing means within said casing, a dust collector located between said chamber and said suction producing means, a suction nozzle communicating directly with said chamber and mounted at one end of the casing, and means at the other end of said casing for connecting a suction hose also with said chamber.

3. In a vacuum cleaner, the combination with an elongated casing, of pumping means and a dust separator therein, a removable dirt pan arranged below said separator, a cleaning nozzle detachably connected with the forward end of said dirt pan to deliver into the same, a valve in said nozzle, and a suction hose adapted to be connected through the rear end portion of said casing with the space above said dirt pan.

In testimony whereof I affix my signature.

JOB HUTCHINSON.
